UNITED STATES PATENT OFFICE.

TAYLOR S. BUCK, OF NEW YORK, N. Y.

CHECK-PROTECTOR STAMP.

No. 851,062.

Specification of Letters Patent.

Patented April 23, 1907.

Application filed January 31, 1906. Serial No. 298,762.

To all whom it may concern:

Be it known that I, TAYLOR S. BUCK, a citizen of the United States, and a resident of New York, in the county of New York and 5 State of New York, have invented certain new and useful Improvements in Check-Protector Stamps, of which the following is a specification.

My invention relates to a check protector 10 stamp for preventing the fraudulent raising of bank check from a smaller to a larger sum, the object being to provide a check protector which will not emboss or puncture the paper, or otherwise thicken or weaken it 15 and which is comparatively cheap, easily and quickly applied, and which is perfectly effectual in showing at once any attempt to raise the check.

In the accompanying drawings, to which 20 reference is made, and which form a part of this specification: Figure 1 is a sectional elevation of my new check protector. Fig. 2 is a sectional plan view taken on line $x-x$ of Fig. 1. Fig. 3 is a bottom view of the check protector, and Fig. 4 is a sectional plan view on line $y-y$ of Fig. 1, showing the top of the protector.

In the drawings 2 designates the body of the check protector stamp, 3 the handle, 4 30 the permanent or stationary type or die carried by the body 2, and 5 the index pointer which is mounted upon the lower end of the journal 6, which in this instance is the lower end of the handle. The permanent or stationary die 4 comprises a series of numbers 35 as shown in Fig. 3 designating sums of money, and as here shown the numbers run from 5 to 105, but it is manifest that any sums of money may be designated either by 40 figures or other characters. The characters are by preference formed as a part of a soft india rubber ring or bed 7 secured to the under surface of the body 2. The index pointer is by preference formed as a part of a soft 45 india rubber disk 8, and on this disk is formed letters to print the words "Not over" and the word "dollars."

On the top of the body 2 is placed or 50 formed a dial 9 which corresponds to the printed character on the bottom of the body; and the handle 3 is provided with a pointer 10 which corresponds with the index pointer 5 so that by turning the handle in the aperture 12 in the body so that the pointer 10 indicates any desired number on the dial 9, the 55

index pointer 5 will in printing denote the same number.

The journal 6 of the handle is formed with a circumferential groove 13 in its outer surface, and the body 2 is formed with one or 60 more, preferably two, passages 14, 14, which intersect the groove in the handle, and in these passages are inserted rods or pins, 15, preferably two brass rods, so that they engage with the groove and lock the handle in 65 place, but at the same time allow it to be rotated but under friction from contact with the rods. A screw 16 is inserted in the body so that its inner end impinges upon one of the 70 said rods. By means of this screw the rod against which it operates may be adjusted or pressed inward to take up wear and to regulate the tension upon the handle.

When the handle is turned so that the pointer 10 indicates the number on the dial 75 9 which most nearly corresponds with the amount for which the check is drawn, the impression of the protector is placed upon the check. In this way the index 5 in the print or impression on the check indicates 80 the amount for which the check is drawn, and in any effort to raise the check, the print or impression of the pointer and of the other matter on the disk would have to be eradicated and another print or impression made, 85 and this being a practical impossibility without detection, the protector stamp becomes a perfect safeguard against the raising of checks.

Having thus described my invention, what I claim as new and desire to secure by Letters Patent, is—

1. The main body having an aperture therein and formed with a hole intersecting the said aperture, said body being formed with another hole intersecting said first mentioned hole, a screw inserted in said last mentioned hole, a journal having a circumferential groove formed therein, and a rod inserted in said first mentioned hole and lying in 95 said groove, substantially as described. 100

2. A main body having an aperture therein, a handle formed with a groove and journaled in said body, a friction piece held by said body and groove and a lateral adjusting screw for said friction piece, substantially as 105 described.

TAYLOR S. BUCK.
